CHANDELIER CRYSTAL

Arnold A. Schonbek, 4918 Mira Road,
Montreal 248, Quebec, Canada

Filed Dec. 11, 1973, Ser. No. 423,771

Term of patent 14 years

Int. Cl. D26—99

U.S. CL. D48—14

Fig. 1

Fig. 2

FIG. 1 is a plan view of a chandelier crystal of my new design.

FIG. 2 is a side view of the chandelier crystal shown in FIG. 1.

The bottom of the crystal is identical to the top as shown in FIG. 1.

I claim:

The ornamental design for a chandelier crystal, as shown and described.
